(57) **CLAIM**

The ornamental design for a tape measure housing, as shown and described.

DESCRIPTION

FIG. 1 is a front perspective view of a first embodiment of a tape measure housing showing our design.

FIG. 2 is a left side view of the first embodiment.

FIG. 3 is a right side view of the first embodiment.

FIG. 4 is a front view of the first embodiment.

FIG. 5 is a rear view of the first embodiment.

FIG. 6 is a top view of the first embodiment.

FIG. 7 is a bottom view of the first embodiment.

FIG. 8 is a front perspective view of a second embodiment of a tape measure housing showing our design.

FIG. 9 is a left side view of the second embodiment.

FIG. 10 is a right side view of the second embodiment.

FIG. 11 is a front view of the second embodiment.

FIG. 12 is a rear view of the second embodiment.

FIG. 13 is a top view of the second embodiment; and,

FIG. 14 is a bottom view of the second embodiment.

The broken lines are environmental only and form no part of the claimed design. The surface stippling represents a contrast of color, texture, or material.
